Lyman E. Dodge
ATTORNEY

UNITED STATES PATENT OFFICE.

EDWARD F. KNOWLES, OF ALBANY, NEW YORK.

RAILWAY-SIGNALING PIPE-CARRIER-FOUNDATION TOP.

Application filed January 15, 1924. Serial No. 686,272.

To all whom it may concern:

Be it known that I, EDWARD F. KNOWLES, a citizen of the United States, and a resident of the city of Albany, in the county of Albany and State of New York, have invented a new and useful Railway-Signaling Pipe-Carrier-Foundation Top, of which the following is a specification.

This invention relates to railway signaling and particularly to foundations used therein and more especially to what is commonly known as a top for the well known pipe carrier foundation.

It is well known to those skilled in the art of railway signaling that in what are known as mechanical plants there are pipe lines, so called, which are a plurality of ordinary pipes positioned one beside the other and parallel to each other and form the connecting means between a lever in a tower and a switch, signal, derail or other function on the roadway alongside of or between the track rails. These pipe lines are supported for free and easy movement by means of what are known as pipe carriers which consist in general of a frame having a roller positioned above the pipe and another roller positioned below the pipe. These rollers are so mounted as to easily turn and the pipe positioned therebetween and resting thereagainst is thereby so mounted as to be movable with the minimum of manual effort exerted by an operator in an adjacent tower by the operation of a lever connected to the pipe. The pipe carriers are supported in accordance with well known practice on what is known as a pipe carrier foundation top. This top is in accordance with general custom made either of wood or of metal and is bolted or otherwise securely fastened to a mass of concrete buried in the earth and called the pipe carrier foundation.

Practice has demonstrated that the tops as now used if made of wood due to their proximity to the earth soon absorb sufficient moisture to become rotten and unfit for their purpose. Practice has also demonstrated that metal tops soon become rusted and weak. Both types of tops have to be renewed at too frequent intervals.

It is an object of applicant's invention to provide a pipe carrier foundation top which will obviate the disadvantages of the known

types of tops in so far as susceptibility to weather conditions and moisture is concerned.

It is a further object of applicant's invention to provide a pipe carrier top of such a nature that its installation will be facilitated.

Other objects and advantages of applicant's invention will appear as the description of the particular physical embodiment selected to illustrate the invention progresses and the novel features of the invention will be particularly pointed out in the appended claims.

In describing the invention in detail and the particular physical embodiment selected to illustrate the invention reference is had to the accompanying drawing, wherein has been illustrated a particular preferred physical embodiment of the invention, and wherein like characters of reference designate corresponding parts throughout the several views, and in which:

Figure 1 is a cross sectional view of a pipe carrier foundation top embodying the invention; Fig. 2, is a side elevational view, with parts broken away to more clearly show the construction, of a pipe carrier top embodying the invention; Fig. 3 is a perspective view of another form of pipe carrier top embodying the invention; Fig. 4, is a side elevational view illustrating the means for combining a plurality of pipe carrier foundation tops embodying the invention; Fig. 5, is a detail view illustrating a method of fastening a pipe carrier to a foundation top such as is illustrated by Fig. 3.

Numerical 1, designates what is generally known as a pipe carrier foundation. This is generally a mass of concrete formed generally as a parallelopipedon although this is not the only form of pipe carrier foundation used and applicant desires to have it understood that his pipe carrier foundation top is not usable solely with this form of pipe carrier foundation.

The letter T designates generally a pipe carrier top as devised by applicant. This pipe carrier top T has a substantially flat upper face 2, except for the elongated bolt nut receiving recesses, as 3. The top T has a substantially flat lower face 4 except for the bedding facilitating recess 5. The ends 6 and 7 of the top T are at substantially a

right angle to the top and bottom faces 2 and 4 respectively. The sides of the pipe carrier top are identically but reversely formed. They consist of a face as 8 and another face as 9 both substantially at a right angle to the top and bottom faces but the face 9 is offset laterally from the face 8 thereby forming the shoulder 10 inclined preferably slightly upwardly from the face 9. The recess 3 is of substantial uniform width throughout and is as shown by Fig. 1 and connects with a bolt orifice 11 which is of a width as shown by Fig. 1 sufficient to allow a bolt as 12 to pass therethrough but is elongated as shown by Fig. 2. Shoulders as 13 and 14 are formed upon which a nut as 15, or if a washer as 16 is used, may rest. The installation of applicant's pipe carrier foundation top is accomplished by placing the top as shown by Figs. 1 and 2 upon a pipe carrier foundation 1 so that it will be positioned as shown by these figures. The top will rest securely upon the foundation, and as an aid to this, the bearing facilitating recess 5 has been formed so that the top rests on the foundation only along a narrow strip thereof adjacent each edge as shown by Fig. 2 so that there is but slight if any tendency for the top to rock. The foundation 1 has orifices as 17 in each side thereof. Into these orifices the bent end of the hook bolt 12 is placed after the bolt has been passed through the bolt orifice 11 of the top. After the hook bolt 12 has been positioned as shown by Figs. 1 and 2 a washer as 16 is placed thereon and then a nut as 15 is screwed onto the upper end of the hook bolt 12 until the washer 15 is brought to a firm and rigid bearing upon the shoulders 13 and 14. This method of connection assures a firm, rigid and permanent means of attaching the top to the pipe carrier foundation. The pipe carriers, as shown by the fragments as 18, are placed upon the flat upper top 2 of the pipe carrier top and each end thereof is then fastened securely to the pipe carrier top by means of hook bolts as 19, one end of the hook bolt engaging with the hook bolt shoulder as 10 and the other end to the hook bolt being provided with a nut as 20 for drawing the hook bolt against the shoulder 10 and the carrier 18 tightly against the top 2. Fig. 3 illustrates another form of applicant's invention and has been designated T'. It differs from the form shown by Figs. 1 and 2 in that, hook bolts as 19 for attaching the pipe carriers are not to be used. It is provided along each side with pipe carrier bolt recesses 21 spaced apart a distance corresponding to the spacing of the pipes of the pipe line. When applicant's invention is embodied in a form as shown by T'

then ordinary bolts 22 as shown by Fig. 5 will be used instead of hook bolts to secure the pipe carriers 18 to the top.

As many pipe lines consist of so many pipes that one pipe carrier top would not be sufficient to support all of the pipe carriers, therefore, applicant contemplates arranging a plurality of his pipe carrier tops end to end as shown by Fig. 4, each supported by a pipe carrier foundation as 1. Applicant may form all of the pipe carrier tops with a squared end as illustrated by Figs. 1, 2, and 3 so that the several pipe carrier tops will abut each other along a line as shown by 23, Fig. 4. In order, however, to secure a more rigid structure and connect one pipe carrier top with an adjacent pipe carrier top, applicant may arrange the pipe carrier tops with an overhanging portion as shown by 24 which will overlap an under projecting portion 25 of an adjacent pipe carrier top. Each of these portions, the overhanging portion and the under-projecting portion being formed with an orifice, a bolt as 26 may be passed therethrough so as to firmly hold the adjacent pipe carrier tops together. Applicant may make his tops with squared ends at each end as shown by Figs. 1, 2 and 3 or with a squared end at one end and at overhanging portion at the other end as illustrated by the central pipe carrier top of Fig. 4, or he may make the pipe carrier top with an underprojecting portion 25 on one end and an overhanging portion 24 at the other end of the pipe carrier top as illustrated by the extreme right hand top of Fig. 4.

Applicant's pipe carrier top is to be shaped of a plastic material which upon standing will harden so as to have the required strength and preferably of sand, gravel and cement that is, will be made of ordinary concrete preferably but whatever the material, it must be such as will successfully resist the effects of weather when exposed in the open air.

Although applicant has particularly described the construction of one physical embodiment of his invention and explained the operation and principle thereof, nevertheless he desires to have it understood that the form selected is merely illustrative, but does not exhaust the possible physical embodiments of the idea of means underlying his inventions.

What I claim as new and desire to secure by Letters Patent of the United States is:

1. A pipe carrier foundation top formed of hardened plastic material and formed with a substantially flat top face and a substantially flat bottom face formed to provide a bedding facilitating recess and each of the side faces arranged in more than one plane thereby forming shoulders and spaced

channels formed along each side in pairs and opening at the top at the top face and at the bottom at the shoulder and formed with a plurality of elongated shouldered 5 orifices on the longitudinal median line.

2. In a pipe carrier support, in combination: a plurality of spaced foundations; a foundation top on each foundation, each top extending so as to abut an adjacent top

and each formed at one end with an overhanging portion and on the other end with an underprojecting portion and a bolt passing through the overhanging portion of one and the under projecting portion of an abutting top whereby the plurality of tops 15 are securely held together.

EDWARD F. KNOWLES.
